Specification of Letters Patent.

Patented Nov. 1, 1910.

Application filed May 21, 1910. Serial No. 562,674.

To all whom it may concern:

Be it known that we, ERIC G. SAMPSON and ALFRED L. WELHAM, residents of Jamestown, in the county of Chautauqua and State 5 of New York, have invented a new and useful Improvement in File-Holders; and we do hereby declare the following to be a full, clear, and exact description thereof.

Our invention relates to file holders and 10 more especially to followers for such holders adapted to be moved back and forth in the holder and retained therein at any desired position.

The object of our invention is to provide 15 a file holder with a follower which, when locked in position, is held securely against movement and at the same time one which may be readily released so as to move freely in its guides.

20 To these ends our invention comprises the novel features hereinafter set forth and claimed.

In the drawing Figure 1 is a longitudinal section of a file holder with our invention 25 applied thereto; Fig. 2 is a section on the line 2—2 Fig. 1; Fig. 3 is an enlarged front view of a portion of the follower partly in section; Fig. 4 is a like view of follower released; Fig. 5 is an enlarged detail; and 30 Fig. 6 is detail of the spring attaching means; and Fig. 7 is a modified form of our invention.

Referring to the drawings the numeral 2 designates a common form of file holder 35 which is formed of sheet metal comprising the bottom 3, the end 4, the sides 5 and the front 6. Our invention, however, may be applied to other different forms of holders.

The sides 5 are provided at their upper 40 edges with the guideways 7 with the downwardly extending groove portions 8. Above the guideways 7 are formed the teeth or indentations 9. These teeth may be formed in a bar 9^a which is held in the upper portion 45 of the guideway.

The follower 10 consists of a metal plate which is provided with the flange portions 11 around its edge. Secured to the follower plate are the brackets 12 and projecting 50 from said brackets and formed integral therewith are the guide-fingers 13 which enter the guideways 7 and fit down within the grooves 8 of said guideways. These guide-fingers hold the follower in proper

position to move easily to and fro in the 55 guideways without binding.

The locking dogs 14 consist of laterally extending bars which are supported at their rear ends in the guides 15, and at their forward ends pass through openings 15^a in the 60 side flanges of the follower plate. The forward ends of the locking dogs are cut off at an oblique angle so as to readily engage the teeth 9 formed above the guideways. The inner ends of the locking dogs 14 are 65 provided with the openings 16 which are engaged by the cam fingers 17 of the bolt 18. This bolt 18 passes up through an opening 19 in the top of the follower and a spring 20 surrounds the pin 21 on the bolt, said 70 spring being interposed between the bolt 18 and the ledge or stop 22 on the follower plate.

It is apparent that when the bolt 18 is in its normal position, the locking dogs 14 will 75 engage the teeth 9 and the follower will be held securely against movement in the guideways. When, however, it is desired to release the follower and move it in its guideways, the operator simply presses down on 80 the bolt 18 and the cam fingers 17 moving down in the openings 16 in the locking dogs will act to draw said dogs toward each other and release their outer ends from the teeth 9. The follower may then be moved freely 85 to any desired position and by releasing the bolt 18 the spring 20 will raise said bolt and the cam fingers 17 force the locking dogs again into engagement with the teeth 9. In this manner, we provide a very simple and 90 effective means for securing the follower in position and readily releasing the same, the follower being held accurately in alignment so that it cannot become stalled or jammed in such a way as to prevent its free and easy 95 movement when released.

In Fig. 7 we have illustrated a modified form of our invention in which the locking dogs 23 are pivoted to the bell-cranks 24, said bell-cranks being pivoted in turn to the 100 follower plate. The bell-cranks are pivoted to each other and at this pivotal point the bolt 26 is attached, said bolt extending up through an opening in the top of the follower and the spring being interposed between 105 said bolt and the ledge or stop 29. By forcing down the bolt it is apparent that the action of the bell-cranks will be to draw

the locking dogs toward each other and release them and when the bolt is free from pressure the spring will throw the locking dogs back into locking position.

5 What we claim is:

1. In a file holder, the combination of a follower, oppositely arranged guideways extending longitudinally of said holder, locking dogs carried by said follower adapted to engage the opposite sides of said holder, and a spring actuated bolt having cam diverging fingers engaging openings in said locking dogs.
2. In a file holder, the combination of a follower, oppositely arranged guideways extending longitudinally of said holder, locking dogs comprising bars extending longitudinally of said follower and movably supported thereby, said dogs adapted to engage opposite sides of said holder, a spring actuated bolt, and connections between said

bolt and said bars for moving the same simultaneously.

3. In a file holder, the combination of a follower, oppositely arranged guideways extending longitudinally of said holder, said guideways having downwardly extending grooves, guide-fingers on said follower engaging said guideways and having downwardly projecting ends engaging the grooves therein, spring actuated locking dogs adapted to engage opposite faces of the holder, and means for operating said dogs simultaneously.

In testimony whereof, we the said ERIC G. SAMPSON and ALFRED L. WELHAM have hereunto set our hands.

ERIC G. SAMPSON.
ALFRED L. WELHAM.
